UNITED STATES PATENT OFFICE.

STEVE TAKACS, OF HARVEY, ILLINOIS.

FOLDING BABY-CRIB.

1,296,569.

Specification of Letters Patent.

Patented Mar. 4, 1919.

Application filed September 4, 1917. Serial No. 189,446.

To all whom it may concern:

Be it known that I, STEVE TAKACS, a citizen of the United States, residing at Harvey, in the county of Cook and State of Illinois, 5 have invented Folding Baby-Cribs, of which the following is a specification.

My invention relates to folding beds of the type adapted to fold together into a compact arrangement, an object being to 10 provide an improved and simplified bed of this character which may be readily folded together into a comparatively small space, simple to operate and cheap to manufacture.

In the preferred form of my invention 15 I provide side-frames suitably connected by pivoted end-frames so that the end-frames fold between the sides, and a spring mattress frame connected to the sides and arranged to fold between them when they are 20 moved together. I also provide end-gates which swing inwardly of the side frames at the upper part of the bed. Thus by having the end gates between the upper part of the sides, and the mattress spring between the 25 lower part of the sides, they may be folded into a very compact arrangement.

Referring to the accompanying drawing for a better understanding of my invention:

Figure 1 is an isometric view of my im- 30 proved bed;

Fig. 2 is a view of one end of a side-gate showing the method of supporting the sides so that they may be raised and lowered;

Fig. 3 is a sectional view along the line 35 3—3 of Fig. 2, showing the latching device for holding the end-gates; and

Fig. 4 is an end view of the bed partly folded.

Referring more now in detail to the preferred construction of my invention, it comprises a light metal frame-work having four corner posts 1, preferably of metal tubes which are made up into two sides or side-frames, the two end posts 1 of each side-frame being securely connected by tubes 2. Adjustable side gates are provided which are made up of metal tubes 3, 4, 5 suitably connected by supporting rods 6, so as to provide a rigid construction. The side gates 45 are slidably supported upon rods 7, which are secured at their upper and lower ends to the posts 1, and extend through suitable openings in the ends of the tubes 3, 4, 5 so that the side gates may be readily raised 50 and lowered. In order to hold these in their upper position, as shown in Fig. 1, latches 55

are provided preferably in the form of pivoted levers 8, having perforated ends, which surround the supporting rods 7 and are frictionally held against the side thereof by 60 means of the spring 9. In order to lower the side gates, the levers 8 are pressed so as to disengage from the rods 7, whereby the gates may be lowered until clear of the mattress or spring, so that ready access 65 may be had from the side of the bed. These side gates are particularly useful on children's beds or cribs.

End gates 10 are also provided being pivotally attached to corner posts 1 by means 70 of suitable hinges 11 so that these gates 10 may be folded back against the inside of a side gate, as indicated in Fig. 4. These end gates 10 are preferably of light metal construction to conform to the rest of the 75 bed frame work but of course, my invention is not limited to the use of any particular material. The end gates 10 are held in their closed position as indicated in Fig. 1 by means of suitable latches 12, which are held 80 by means of springs 12^a and connected to suitable levers 12^b, the latching end 12 having an inclined or beveled surface adapted to snap into a hole in a tube 13 of the end gates 10, as indicated in Fig. 3. These end-gates when closed also help to brace the side-frames.

The bed is adapted to fold up in the manner as indicated in Fig. 4 and for this purpose I provide connecting bars 14, 15 suitably pivoted at 16, 17 respectively to the corresponding corner post, and also pivotally connected in the middle at 18, 19 and connected together by connecting rods 20. Thus, when the connecting rod 20 is pulled 95 upwardly the bars 14, 15, and side frames are drawn together as shown in Fig. 4.

A suitable mattress spring frame is provided being pivotally carried by rigidly supported longitudinally extending bars 22, so 100 that the mattress spring frame is folded downwardly as indicated in Fig. 4 while the cross-connecting rods move upwardly.

In order to fold the bed from its open position as shown in Fig. 1 the end gate 105 latches 12 are first pressed and the end gates 10 swung inwardly against a side gate as indicated in Fig. 4. The end frames 14, 15 are then moved upwardly as indicated in Fig. 4, and the mattress spring frame 21 110 moved downwardly, these parts folding up as the two sides are moved together. It is

to be understood of course, that in Fig. 4, the bed is shown only partly closed but that the folding operation continues until the two sides are moved together against the 5 end gates and mattress spring frame, thus securing a very compact arrangement. In order to open the bed the sides are pulled apart and then the end frames 14, 15 are pressed downwardly until they assume the 10 position shown in Fig. 1. The end gates 10 are then swung outwardly to the position shown in Fig. 1, where they are held by the catches 12, as shown in Fig. 3.

For the purpose of illustrating my invention, I have shown it as a bed constructed of a light metal framework but it is to be understood that my invention is not limited to this particular construction, but that wood or other material may be used as desired. I 15 also understand that many changes and modifications of my invention as shown may be readily made and therefore I do not desire to be limited to the exact arrangement shown or described but aim to cover all that 20 which comes within the spirit and scope of the appended claims.

I claim—

1. A folding bed made up of a light metal framework comprising four corner posts, 30 side frames connecting each pair of posts at the upper ends of the posts, a foldable mattress spring-frame pivotally connecting the side frame and corner posts intermediate

thereof, end frames pivotally connecting the side frames, swinging end gates at the upper ends of the corner posts adjacent the side frames, whereby said end gates may be swung inwardly against the side frames at the upper part of the bed and the mattress-spring frame swung downwardly below the 40 end gates when the side frames are folded together so as to form a compact structure.

2. A folding bed comprising side frames, end bars pivotally connected at each end of the side frame and at their centers whereby the side frames may be moved into intimate relation and the end bars folded between, and end gates normally in position over the end bars to prevent folding thereof, but movable inwardly against the side frames 45 whereby the end frames may be moved and the sides folded together.

3. A folding bed comprising side frames, end frames pivotally connecting the side frames so as to permit folding together of 50 the side frames, a mattress spring frame suitably connected to the side frames, said spring and end frames being pivotally constructed so as to permit one to fold upwardly and the other downwardly between 60 the side frames, and end gates adapted to swing inwardly against the side frames but normally in position to prevent a folding movement of the upwardly movable frames.

STEVE TAKACS.
